(57) **CLAIM**

The ornamental design for an electronic component cabinet, as shown and described.

DESCRIPTION

FIG. 1 is a front, elevation view of an electronic component cabinet, showing my new design;
FIG. 2 is a rear, elevation view thereof;

FIG. 3 is a right-side, elevation view thereof;

FIG. 4 is a left-side, elevation view thereof;

FIG. 5 is a top plan view thereof; and,

FIG. 6 is a bottom plan view thereof.

The broken and/or dashed lines depict environmental structure and do not form a part of the claimed design.
